UNITED STATES PATENT OFFICE.

ALBERT GOODYEAR, OF NEW HAVEN, CONNECTICUT.

HARVESTING MACHINE.

SPECIFICATION forming part of Letters Patent No. 453,471, dated June 2, 1891.

Original application filed August 2, 1886, Serial No. 209,719. Divided and this application filed March 5, 1888. Serial No. 266,120.
(No model.)

To all whom it may concern:

Be it known that I, ALBERT GOODYEAR, a citizen of the United States, residing at New Haven, county of New Haven, State of Connecticut, have invented a new and useful Improvement in Harvesting-Machines, of which the following is a specification.

Heretofore, on August 2, 1886, I filed in the United States Patent Office an application for Letters Patent, Serial No. 209,719, which embodied the subject-matter of the present application, and this application is in fact a division of application, Serial No. 209,719, filed in compliance with the recommendation of the Patent Office. Reference will therefore be had to the description and drawings in the original application for a full description of the parts with which the devices set forth in the present application are combined and attached.

The first part of my invention consists in the construction of an expandable and contractible frame by introducing a joint between that portion of the frame supporting the main machine and that portion supporting the grain receiver or apron, which serves as a platform on which the grain falls as it is cut.

The second part of my invention consists in the construction of the grain-receiver with a hinged joint, and combining therewith a cutting device, so that the grain-platform and the cutting device may be raised independently of the grain-wheel and the frame for the purpose of transporting the machine in a small compass.

The third part of my invention consists in combining with the features last referred to a sliding joint in the frame, whereby when the finger-bar and the grain-receiver are swung upward the frame may be contracted.

The fourth part of my invention relates to the reel, which is made contractible and expandable, in the manner hereinafter more fully set forth, and which is also hinged.

In the drawings I have represented sufficient of a harvesting-machine to convey the manner in which the various parts claimed herein are to be combined; but I do not desire to be understood as limiting myself to the precise form which I am about to describe,

since I am aware that mechanics in carrying out my invention would probably introduce many variations in the form of apparatus.

Figure 1 is a front view of the grain end 55 of the machine, showing the reel in its expanded position with the cutting devices and grain-platform all in position ready for operation. Fig. 2 is a rear view of the same end 60 of the machine, showing the reel, grain-platform frame, grain-platform, and cutting devices in their folded position. Fig. 3 is a plan view of the same end of the machine, taken on the line 3 3, Fig. 1. Fig. 4 is a cross-section of the end bracket to which the finger-bar is pivoted, showing the manner of pivoting the finger-bar thereto. Fig. 5 is a cross-section of one of the brackets supporting the finger-bar intermediate its two ends. Fig. 6 is a cross-section of the bracket supporting 70 the finger-bar on its free end. Figs. 7 and 8 are detail views showing the manner of securing the reel-shaft 49 in position on the pipe q.

The frame of the machine is fully described 75 in the application, Serial No. 209,719, before referred to. The frame is made up of tubes or piping.

The main frame of the machine consists of pipes extending along the front and along the 80 rear and across both ends of the machine underneath. The front and rear pipes just referred to are made up of two sections a' b' b'. The sections a' b' are enough smaller in diameter than the sections a b to fit snugly 85 within the latter, so as to form a telescope-joint therewith.

c is the pipe which connects the two pipes a' b' at one end of the machine. The connecting-pipes for the pipes a and b at the other 90 end of the machine I have not shown. The main frame of the machine is thus made in the form of a parallelogram, which, by the telescope-joint already referred to, may be lengthened or shortened, as required. 95

1 is the ground-wheel, which is mounted upon a shaft having its bearings on the main frame of the machine.

2 is the grain-wheel. The axle of the grain-wheel is secured at its inner end by a slotted 100 connection, so as to be vertically adjustable.

Upon the shaft of the ground-wheel is

mounted a spur-wheel 4, which gears with the pinion 5, and thus drives the shaft 6, on which is mounted the bevel-gear 7. This bevel-gear in turn drives the shaft *w*. Upon one end of this shaft *w* is mounted the crank 8, which, by the pitman-rod 9, communicates a reciprocating motion to the finger-bar 10. The reel, which is shown in Fig. 1 open and in Fig. 2 closed, turns upon the shaft 49. This shaft has its bearing in one end on the pipe *q* and at the other end in a proper upright on the main frame. I have shown the bearing of the reel-shaft on the pipe *q* as a U-shaped socket adjustable on the said pipe. When in operation, the shaft is clamped in this U-shaped socket by means of the cap, which can be removed if it becomes necessary to contract the reel. The shaft 49 is turned by means of the worm-gear 50, which is driven from the operative parts of the machine by any suitable connections.

51, 52, 53, and 54 are the strips or bats which strike the grain. Each of them is connected with the sheaves on the shaft by the jointed arms 55 56.

57 are rods connecting every two pair of rods 55 and 56 at their junction. Rod 58 connects the end of rod 57 with a sliding sleeve 60 on the shaft, there being one rod 58 for each rod 57. Rods 59, of which there are four, connect 51, 52, 53, and 54 with the sliding sleeve 61 on the shaft. The relative dimensions of the parts are substantially as shown. The sleeves 61 and 60 are connected with a lever 62, which is used in closing the reel. This closing is accomplished by moving the sleeves in the direction of the arrow, which will cause the rods 55 and 56 to move, respectively, in the direction of the arrows crossing them. The reel may thus be closed, as shown in Fig. 2. The same means may be employed to adjust the beaters 51 52 53 54, so as to strike the grain at various heights from the cutters, using the reel partly or wholly open, as may be desired or required.

At 63 is a joint in the shaft 49, which enables the shaft when the reel is folded to be swung around, so as not to project beyond the grain-platform, as shown in Fig. 2.

50 I will now describe the provision for folding the platform and cutting devices. 64 is a bracket clipped to the pipe *a'* at its extremity, and which is provided with a slot 80, opening upward to receive the extremity of 55 the finger-bar, as shown in Fig. 6. 65 66 are respectively brackets of a similar character, which also support the bar. On bracket 66 the finger-bar is pivoted. Thus when in position to operate the finger-bar rests in the three brackets, but it may be turned up into the position shown in Fig. 2 and in dotted lines in Fig. 1. The grain-platform is hinged at 67, so that by separating it from the divider *o* its outer portion may be folded from the position in Figs. 1 and 3 to the position in Fig. 2. As soon as the bar and grain receiver or plat-

form have been folded, as described, the pipe-sections *a' b'* may be pushed into sections *a* and *b* until the wheel 2 and divider *o* occupy the position shown in Fig. 2, where they may be secured by the hook 68. When in this condition, the machine is in comparatively a small compass and is convenient to transport.

69 is a catch secured to the seat-support, by which the finger-bar may be held in its raised position.

I claim—

1. In combination with the front and rear tubing *a* and *b* and the tubing *a'* and *b'* telescoping with the same, the hinged grain-platform, substantially as described.

2. In combination, the expandible and contractible frame, the pivoted cutter or sickle bar, and the folding grain-platform, substantially as described.

3. A harvester-frame made up of two sections forming a sliding joint with each other, one connected with the ground-wheel and the other with the grain-wheel, in combination with the folding grain-platform, substantially as described.

4. A harvester-frame made up of two sections forming a sliding joint with each other, and the hinged cutter or sickle-bar supported at one end by the bracket 66, secured to one section of the frame, and at the other end by the bracket 64, secured to the other section of the frame, whereby when the cutter or sickle bar is folded the frame may be shortened, substantially as described.

5. In combination, the extensible and contractible frame, the folding platform, and the reel-shaft 49, hinged as at 63, substantially as described.

6. In combination with the cutter or sickle bar and the grain receiver or platform, a reel constructed with axis 49, with beaters 51 52, with jointed radial arms 55 56, with link 57, connecting the radial arms with rods 58 and 59, connecting, respectively, the inner and outer links of said jointed radial arms with the axis, said rods 58 being connected with a handle for the operator, substantially as described.

7. In a harvesting-machine, a reel provided with beaters, and means, substantially as specified, for folding the same about the reel-shaft, and a reel-shaft jointed at its inner end to permit the reel to swing to the side of the machine after being folded, substantially as specified.

8. In a harvesting-machine, the combination, with a folding grain-platform, of a pivoted expandible reel, substantially as specified.

9. In a harvesting-machine, the combination, with a pivoted cutter-bar, of a pivoted and expandible reel, substantially as specified.

ALBERT GOODYEAR.
